UNITED STATES PATENT OFFICE.

HENRY McCUE, OF KANSAS CITY, MISSOURI, AND JOHN DAVIS, OF TERRE HAUTE, INDIANA.

BRICK-KILN.

SPECIFICATION forming part of Letters Patent No. 239,053, dated March 22, 1881.

Application filed June 23, 1880. (No model.)

To all whom it may concern:

Be it known that we, HENRY McCUE, of Kansas City, in the county of Jackson and State of Missouri, and JOHN DAVIS, of Terre Haute, in the county of Vigo and State of Indiana, have invented a new and useful Improvement in Brick-Kilns, of which the following is a specification.

Brick-kilns as heretofore constructed are objectionable in many respects. Such objections may be stated, briefly, as follows: The vault-walls usually occupy the full length of the kiln, thereby requiring skilled labor for framing the timbers to be anchored to the kiln-walls for the roof. This also involves the use of considerable material and is expensive. The compartment-walls between each set of openings require extra room, material, and labor, and for no practical purpose. The atmospheric air is supplied through zigzag passages, which are liable to be stopped by masonry. Such openings are also insufficient as air-chambers, and the walls being solid, except at the small air-passages, are not durable. In the use of ashes, sand, or other material supplied by a chute to fill the openings and regulate the heat, such method is unhandy and unreliable.

The object of our invention is to construct a kiln free from such objections; and our invention consists in certain novel features of construction, which will be more particularly described hereinafter with reference to the accompanying drawings.

In the drawings, Figure 1 is a side elevation of a kiln, one furnace only being shown, and the base being partially removed to show the construction more clearly. Fig. 2 is a vertical cross-section on line $x-x$ of Fig. 1. Fig. 3 is a cross-section of the furnace on line $y-y$ of Fig. 2. Fig. 4 is a cross-section of the vault on line $z-z$ of Fig. 2.

Similar letters of reference indicate corresponding parts.

A is the kiln, composed of side walls, $a a$, end walls, b , and base c , and built in any desired form and of the desired size. These walls are made of brick or other suitable material, and thicker at the base than in the upper portion. Through the base of the side walls there are openings d at regular distances apart,

which openings vary in size according to the range of heat, and above these openings d the kiln-walls are grooved vertically to a sufficient height above the coping for receiving the dampers e . The openings d are surrounded by fire-linings, and between the fire-linings of the several openings air-spaces f are formed in the kiln-walls, which spaces communicate with each other and with the passages g that open to the outer air. The amount of air admitted to the spaces f may be regulated by using a bat of soft material in the openings g , and the heated air may escape through openings at the top of the coping, which openings are prolongations of the spaces f . At the inner corners of the kiln-walls, above the base, the material is filled in, as at h , thereby filling the cold corners, strengthening the walls by throwing the heated air outward, preventing loss of heat.

The side walls, a , are formed at the outer side with pillars i , which are placed at suitable intervals to include three or more openings, d . Posts k , of suitable size, and of a length to extend from five to seven feet above the walls, are set in the ground and securely fastened to the pillars i by bolts bedded in the masonry, which posts are braced by plates k' and cross-rods l , that are secured to the upper ends of the posts. The walls and roof are thus substantially supported. The end walls are supported by posts l' in the same manner. The passage-way for removal of the articles when burned will be between the two center posts of the end walls, and will be temporarily filled with suitable material while the kiln is in operation. The posts l' will be placed to support the filling as well as the permanent wall, and the posts are braced by rods m' from the plates m to plates k' .

The combustion-vaults B and furnaces C are built outside of the side walls, a , between the posts k . Each vault is built firmly to the base-walls of the kiln to include three or more openings, d , and are uniformly arranged at opposite sides of the kiln. The side walls, n , of the vaults are made hollow and provided with inlets n' for admission of air to the space, which space also communicates by openings under the arch to the interior of the vault. Through

the side walls, under the arch, there are sight-holes *o*, and in the front walls there are sight-holes *o'*, through which observation may be made to the interior of the kiln through openings *d*.

The walls of the furnace *C* are constructed in front of the vault *B*. The side walls, *p*, are hollow, with openings to the outer air and escape-holes to the interior of the furnace, as shown in Fig. 3. In the end walls, *q*, under the arch, there are sight-holes *q'*. There are also sight-holes in the doors *r* of the furnace, which holes are provided with swinging wickets *s'*, by which the holes may be closed. The side walls, *p*, are sustained by posts *t*, that are planted in the ground and connected at their upper ends by a cross-bar, *t'*. To this cross-bar *t'* notched standards *u* are secured, and upon the side of the kiln are hung the dampers *v*, that engage with the notched standards *u*. The dampers *e* are hung from levers *v* by adjustable rods or chains, and may be made of metal, fire-clay, or other suitable material.

This construction furnishes a kiln that will be durable, as the walls are protected from excessive heat by the interior air-space, with their inlets for cool air and outlets for heated air. The furnaces being formed separate from each other, there is opportunity and space for setting the supporting-posts of the wall. The

kiln is convenient for use, and the progress of the work may be readily observed.

This kiln may be used for firing tiling, brick, or earthenware of any kind. The pillars *i* protect the supporting-posts from the effects of the heat. The door-sills and grate-bars of the furnace are constructed so as to permit their renewal, as required. By the use of the dampers the heat is placed under full control of the operator, and by closing them while adding fuel cold currents will be prevented from entering the kiln.

Having thus described our invention, we claim as new and desire to secure by Letters Patent—

1. In a kiln, the combination, with walls *a* and base *c*, provided with openings *d* at regular intervals, of the dampers *e*, the air-spaces *f* between the fire-linings, and the passages *g*, having a bat of soft material, as and for the purpose described.

2. In kilns, the corner-fillings *h*, combined with the walls *a* *b*, substantially as and for the purposes specified.

HENRY McCUE.
JOHN DAVIS.
